UNITED STATES PATENT OFFICE.

HENRY PANNILL, OF PETERSBURG, VIRGINIA, ASSIGNOR TO THE VIRGINIA COAL SAVING AND HEAT REGULATING COMPANY, OF SAME PLACE.

DESIGN FOR A FIREPLACE REGULATING-PLATE.

SPECIFICATION forming part of Design No. 33,040, dated July 31, 1900.

Application filed November 6, 1899. Serial No. 736,050. Term of patent 14 years.

To all whom it may concern:

Be it known that I, HENRY PANNILL, a citizen of the United States, residing at Petersburg, in the county of Dinwiddie and State of Virginia, have invented and produced a new and original Design for a Fireplace Regulating-Plate, of which the following is a specification, reference being had to the accompanying drawings, forming part thereof, in which—

Figure 1 is a face view, and Fig. 2 an edge view, of a regulating-plate, showing my new design.

As shown in the drawings, the leading or material feature of my design consists in the design forming the subject-matter of the accompanying illustration.

The plate has the general rectangular form with its edges scalloped at A, with the scallops joining each other and the scalloped por-

tion extending around both ends and one side 20 of the plate, as shown in Fig. 1. The plate is corrugated longitudinally from side to side, as indicated in Fig. 1 and shown more clearly in Fig. 2, and it is provided with openings B in the form of vertically-elongated slots, as 25 shown in Fig. 1, the central one of which communicates with a transversely-extending notch C, as shown in Fig. 1.

Having described my invention, what I claim as new, and desire to secure by Letters 30 Patent, is—

The design for a fireplace regulating-plate, as herein shown and described.

HENRY PANNILL.
